United States Patent Office

Des. 230,824

Patented Mar. 19, 1974

230,824

LETTER OPENER

William L. Goffe, 301 Burnette Road,
Webster, N.Y. 14580

Filed Dec. 7, 1972, Ser. No. 312,826

Term of patent 14 years

Int. Cl. D18—04

U.S. Cl. D8—102

FIG. 1

FIG. 2

FIG. 5

FIG. 3

FIG. 6

FIG. 4

FIG. 1 is a top plan view of a letter opener, showing my new design;

FIG. 2 is a left side elevational view thereof;

FIG. 3 is a right side elevational view thereof;

FIG. 4 is a bottom plan view thereof;

FIG. 5 is a rear elevational view thereof; and

FIG. 6 is a front elevational view thereof.

I claim:

The ornamental design for a letter opener, substantially as shown.
